DES. 1992

Martin Party, of New York, N.Y.

Letters Patent No. 1992 Dated Oct 18, 1864.

Design for a Photographic Album Leaf.

The schedule referred to in these Letters Patent and making part of the same.

To all whom it may concern:

Be it known that I, Martin Party of No. 3 Marion Street in the City, County and State of New York, have produced a new and ornamental design for Photographic Album Leaves, etc. and I do hereby declare that the following is a full, clear and exact description thereof, which will enable others skilled in the art to produce and use the same, reference being had to the accompanying drawing forming part of this specification.

The drawing represents a face view of a photographic album leaf ornamented according to this design.

This invention, which is applicable to photographic album leaves, or to frames or borders for photographic pictures, made of paper, card board or other suitable material consists in ornamenting such leaves, borders or frames with a string of holes extending all around the embossed frames or borders in such a manner that by the addition of this string of holes a highly ornamental and novel effect is produced.

2

OFS. 1992

The leaf A is produced with an opening large enough to exhibit plainly the picture on an ordinary photographic card such as are generally used in photographic albums. This hole is provided with a border a, consisting of a series of scallops, the rear ends of which join a raised moulding. This moulding is surrounded by a string of holes d, giving to the whole a highly ornamental and novel appearance.

What I claim as my said desire to secure by Letters Patent is the string of holes d surrounding the border a, as shown and described.
